UNITED STATES PATENT OFFICE.

MORDAUNT E. PITTMAN, OF CENTER, TEXAS.

INDICATING AND TESTING APPARATUS.

1,265,953.

Specification of Letters Patent.

Patented May 14, 1918.

Application filed April 18, 1918. Serial No. 91,950.

To all whom it may concern:

Be it known that I, MORDAUNT E. PITTMAN, a citizen of the United States, residing at Center, in the county of Shelby and State of Texas, have invented new and useful Improvements in Indicating and Testing Apparatus, of which the following is a specification.

This invention is an improved indicating and testing apparatus for use on gasolene and other like engines having one or more cylinders to test the cylinders and indicate which of them are misfiring or have leaky valves or rings and thus facilitate adjustments and repairing; to also indicate when the carburetor is properly adjusted to produce a mixture having maximum explosive power, and to also store burned gas or carbon dioxid at approximately the same pressure as that produced by explosion in the engine cylinders. A scrubber and cooler 22 is connected to this reservoir and is also connected by a pipe 23 to the nipple 6. Associated with said nipple 6 is a cut off valve 24, the stem of which is threaded in the nipple 10. Said nipple 10 has a stuffing box 25. The nipple 7 discharges into the atmosphere, preferably through a pipe 26 which leads to a suitable point. A regulating and cut off valve 27 is associated with the nipple 7 and has its stem threaded in the nipple 11. Said nipple is provided with a stuffing box 28.

The invention consists in the construction, combination, and arrangement of devices, hereinafter described and claimed.

In the accompanying drawings:

Figure 1 is a diagrammatic plan, partly in section, of an indicating and testing apparatus constructed and arranged in accordance with my invention.

Fig. 2 is a detail sectional view of one of the cylinder pressure valves.

Fig. 3 is a detail plan of the same.

Fig. 4 is a detail sectional view showing a modified construction of cylinder pressure valves.

In accordance with my invention, I provide a header 1 which forms a chamber 2 and is provided on one side with a series of nipples 3, one for each engine cylinder 4, and is also provided with nipples 5, 6, 7. On the side, opposite the nipples 3 are nipples 8, a nipple 9 is opposite the nipple 5, a nipple 10 is opposite the nipple 6, and a nipple 11 is opposite the nipple 7. Each engine cylinder 4 is provided with a pressure valve 12, the casing of which is connected to the header by means of a pipe 13, each pipe 13 being connected to one of the nipples 3 and being provided with a stuffing box 14. A cut off valve 15 is associated with each pressure valve and has a stem threaded in one of the nipples 8 and each nipple 8 being provided with a stuffing box 16.

A pressure indicating gage 17 of suitable construction is connected to the nipple 5 by a pipe 18 and said nipple 5 is associated with a cut off valve 19, the stem of which is screwed in the nipple 9 and said nipple 9 being provided with a stuffing box 20. A reservoir 21 is provided for the storage of burned gas or carbon dioxid at approximately the same pressure as that produced by explosion in the engine cylinders. A scrubber and cooler 22 is connected to this reservoir and is also connected by a pipe 23 to the nipple 6. Associated with said nipple 6 is a cut off valve 24, the stem of which is threaded in the nipple 10. Said nipple 10 has a stuffing box 25. The nipple 7 discharges into the atmosphere, preferably through a pipe 26 which leads to a suitable point. A regulating and cut off valve 27 is associated with the nipple 7 and has its stem threaded in the nipple 11. Said nipple is provided with a stuffing box 28.

The cylinder pressure valves 12 are identical in construction. Each of said valves has a casing 29 provided with a nipple 30 to be screwed in a threaded opening leading to the combustion chamber of one of the engine cylinders. In the bore 31 of the nipple is a seat 32 in which operates an inwardly opening valve 33. The bore 31 leads to a chamber 34 in the casing 29, which chamber is closed by a diaphragm 35 which is held against an annular shoulder 36 by a ring 37 which is screwed in place and is provided with an arched cross bar 38.

A lever 39 is arranged in the chamber 34, is pivotally mounted at one end as at 40 and is provided at its free end with an adjusting screw 41. Said screw has a disk 41a secured thereto near its lower end, which disk bears on the upper end of a coiled spring 42 which bears on and keeps the valve 33 normally closed. The tension of the spring may be varied as required by turning the adjusting screw. A lever 43 is also arranged in the chamber 34, is pivotally mounted at one end as at 44 and is provided near its free end with an adjusting screw 45 which bears on the lever 39 at a point near the pivot and fulcrum 40 of the latter. Said lever 43 also has a stud or thrust member 46 which bears against the inner side and at the center of the diaphragm 35. An adjusting screw 47 is threaded in a central opening in the cross bar 38 and bears on the outer end of a spring 110

48, the inner end of said spring bearing against the center of the diaphragm. A stop 49, which is tubular, extends from the cross bar 8 toward the diaphragm and terminates at a point normally a slight distance from the diaphragm.

The operation of my invention is as follows: To test the pressure in the engine cylinders to ascertain whether any of them are misfiring, or the valves of any of them leak, each of the cylinders is tested separately. The engine will be run idly at say half speed, the valve 24 leading from the header to the reservoir will be closed, the valve 19 opened, the valve 27, controlling the discharge from the header to the atmosphere will also be initially closed, and the valve 15 controlling the first cylinder to be tested will be opened, the corresponding valve of each of the other cylinders being closed.

Let it be assumed that the pressure produced by an explosion in the first cylinder under such conditions and when the said cylinder is properly firing and its valves are tight will be 180 pounds. Let it also be assumed that the screw 47 which controls the diaphragm 35 has been properly adjusted. Under such conditions, the pressure caused by the explosions will cause some of the burned gas at each explosion to open the valve 33 and pass through the pipe 13 to the header. In a short time, the pressure in the header will be 180 pounds and this will be indicated by the gage 17. The valve 27 will then be opened slightly to reduce the pressure in the header and maintain such pressure say at 160 pounds.

The valve 15 of the next cylinder to be tested will then be opened and the pressure in the header will be increased if the next cylinder is not misfiring entirely and will be indicated by the gage 17. The valve 15 of the first cylinder should then be closed. If the second cylinder is in the same condition as the first cylinder, the pressure in the header will drop and will stand at 160 pounds, the same as when the first cylinder was tested. If the rings and valves of the second cylinder leak, the pressure in the header will drop below 160 pounds and such condition will be indicated. If the second cylinder is misfiring, the pressure in the header will drop to zero. If the second cylinder is only firing occasionally, the pressure in the header will be very low and unsteady. The cylinders are tested separately in this way and the pressure of each will be tested and compared with that of the one first tested or which is known as the result of tests to be properly operating. During this test, the engine throttle and the spark should remain in one position. If any engine cylinder shows less pressure than others and the steadiness of the gage indicates that it is firing regularly, the compression should be

tested to ascertain whether the valve or rings leak.

To test the compression, the adjusting screw 47 of the pressure valve of the cylinder under test is loosened to permit the compression pressure to lift the valve 33. The pointer and dial 50, 51, of the screw 47 will facilitate the adjustment of said screw and enable it to be restored to initial position at the completion of the test. The engine is revolved by the starter with the spark cut off. The regulating valve 27 should be closed. Then if the valve 15 is opened, the maximum pressure attained in the engine cylinder will be indicated by the gage, said valve 15 should then be closed and the valve 27 opened to relieve the pressure in the header. The regulating valve 27 should then be closed and the valve 15 of the next cylinder to be tested opened, and so on with all of the cylinders. If the rings and valves are tight, on all the cylinders, the pressure of all will be the same. If those of any cylinder are leaking such cylinder will indicate lower pressure than the others. If the engine has no electric starter, the engine should be run in the usual way and the spark cut off from each cylinder while testing its compression.

To charge the reservoir 21, the valve 27 should be closed, the valve 24 opened, and the valves 15 also opened. If only a small quantity of gas is required, then only one of the valves 15 need be opened. The gage 17 will indicate when the desired pressure is reached, the valve 24 can be closed and also the valve or valves 15. The gas thus stored under pressure in the reservoir is cleaned and cooled in the scrubber and cooler 22 and can be used for operating an air starter, a pneumatic jack, for filling tires, operating a horn and for other purposes.

Tests for misfiring can be made while the car is running and when the cylinder which is misfiring is located, the car can be stopped and the spark plug changed, or other repair, with only a minimum loss of time.

The invention can also be used to adjust the carburetor. This is done by running the engine one-half speed with one or more of the cylinders open to the header so that the pressure of the explosion registers on the gage. The valve 27 will be opened slightly so that the pressure can vary in the header as the maximum explosion varies. Let it be assumed that this pressure is 180 pounds with the valve 27 closed, and is 160 pounds with said valve 27 opened. If the carburetor adjustments are then changed, so as to make a better and more explosive mixture, the pressure in the header will increase. If the carburetor adjustment is made so that the mixture is less explosive, the pressure will decrease. By trying different adjustments, the desired mixture can be obtained. Each change of the carburetor adjustment is indi-

cated on the gage so that it is rendered easy for even a novice to adjust the carbureter.

The operation of the valve 12 is as follows: When a cylinder compresses an explosion charge, say to 70 pounds, this gas tends to pass through the opening 31 and to lift the valve 33 but is prevented by pressure on this valve by the spring 48 which is compressed by the screw 47 and the pressure of the diaphragm 35 is communicated to said valve 33 by the levers 39 and 43 and spring 42. When the explosion occurs, pressure in the cylinder rises to say 180 pounds. This lifts the valve 33 and a small proportion of the burned gas under pressure passes into the chamber 34 and from thence through the pipe 13 into the header. Each explosion of the engine cylinder to which the valve 12 is connected causes gas to enter the chamber 34 and as the pressure in such chamber rises the diaphragm is forced against the spring 48, which reduces the pressure of the diaphragm on the lever 43, hence reducing the pressure of the lever 43 on the lever 39 and the pressure of the latter lever on the valve 33. If the diaphragm has an effective area of four square inches and the valve 33 has an effective area of one square inch, a lever-ratio of four on 48 to one on 39 will be required. It will be seen that if the spring 48 is adjusted by the screw 47, so that 71 pounds is required to lift spring pressure from the valve 33, and the compression pressure is only 70 pounds, no compression gas will pass the valve 33. When, however, a pressure exceeding 70 pounds, say 71 pounds, is reached in the chamber 34, the diaphragm will be pushed up against the stop 49. The levers 43 and 39 will be released, and the valve 33 will be free from pressure excepting that of the gas in the chamber 34 and the spring 42. Said spring holds the levers tightly with the stud 46 always in contact with the diaphragm 35 and prevents the levers from moving when the valve 33 opens. Said spring 42 also acts to quickly close the valve 33 against its seat. While the diaphragm is against the stop 49, the valve 33 operates as a check valve, with every explosion of the engine cylinder said valve will be lifted by the gas and this will be continued until the pressure in the chamber 34 approximately equals that in the engine cylinder.

When it is not desired to employ the reservoir 21, the valve 12 as shown in Fig. 2,

may be dispensed with and the form of valve shown in Fig. 4 employed in lieu thereof. In this modified form of valve there is a casing 51 for connection to the engine 60 cylinder, provided with a cross partition 52 forming an opening and seat 53 and dividing said casing into chambers 54, 55. The upper end of the casing is closed by a cap 56. A pipe 13^a leads from the chamber 54 to the header. A pop valve 57 is arranged in the lower portion of the chamber 55, to close downwardly in a seat 58 and is kept normally closed by a spring 59. A ball valve 60 is arranged in the chamber 54 to close 70 on the seat and opening 53, and is kept normally closed by a spring 61. The limit of upward movement of said valve 60 to open the passage 53, is controlled by a tubular stop 62, around the spring 61, and extending downwardly from the cap 56.

Having described the invention, what is claimed is:

1. An indicating and testing apparatus of the class described comprising a header, connections between the cylinders of an engine and the header and each including a valve to close against the back pressure from the header, a gage to indicate pressure in the header, and a regulating pressure relieving 85 valve for the header.

2. An indicating and testing apparatus of the class described comprising a header, connections between the cylinders of an engine and the header and each including a valve 90 to close against back pressure from the header, a gage to indicate pressure in the header, a regulating pressure relieving valve for the header, a storage reservoir connected to the header, and a valve to open or close 95 communication between the header and storage reservoir.

3. An indicating and testing apparatus of the class described comprising a header, connections between the cylinders of an engine and the header and each including a valve to close against back pressure from the header, a gage to indicate pressure in the header, a regulating pressure relieving valve for the header, and means to vary the closing pressure on the first-named valve.

In testimony whereof I affix my signature in presence of two witnesses.

MORDAUNT E. PITTMAN.
